KNITTING MACHINE

Harry N. Sheppard, Maplewood, N. J., assignor to
Scott & Williams, Incorporated, New York,
N. Y., a corporation of Massachusetts

Original application September 8, 1932, Serial No.
632,213. Divided and this application Septem-
ber 2, 1933, Serial No. 688,014. In Great
Britain May 11, 1933

8 Claims. (Cl. 66—48)

This invention relates to a machine for the manufacture of seamless stockings and more particularly to a machine adapted to make an improved heel structure in the stocking.

This application is a division of my application Serial No. 632,213, filed September 8, 1932, which issued as Patent No. 1,932,292 Oct. 24, 1933, and in which I claim the improved stocking and the method of making it. In that improved stocking the heel pocket is formed of a narrowed segment 110 only, that segment preferably being formed in a novel manner and the subsequent knitting of the sole being altered slightly to conform thereto. In a stocking having this improved heel structure the number of courses in the narrowed segment is increased over the number ordinarily found in the narrowed segment of a seamless heel or toe pocket without increasing the number of needles involved in the making of the segment. This changes the shape of the heel by increasing the angle of the narrowed segment at the corner of the heel, so that the necessity for the widened segment is done away with. By increasing the number of courses in the narrowed segment without increasing the number of needles on which it is made, the heel is made compact and solid and, in fact, the congestion of stitches near the point of the heel is so great as to cause the lower end of the suture between the narrowed segment and the sole to turn forward slightly toward the toe of the stocking. In this way the necessary extent of reinforced fabric is produced on the sole of the stocking, but the amount of reinforcement on the side of the heel is reduced slightly. Furthermore it should be noted that owing to the increased angle formed by the segment at the corner of the heel, the suture line of the heel is practically vertical where it is subject to very much less strain than if it were directed toward the point of the heel. The angle formed between the suture line and the direction of the wales in the narrowed segment, combined with the increased number of courses in the narrowed segment, causes the fabric to pucker where the narrowed segment is joined to the sole. In this connection, it is necessary to join together an unequal number of courses, there being more courses in the heel than wales in the sole. In order to avoid puckering along the suture line, it is therefore proposed to slacken some stitches in the sole, the preferred form being the slackening of all the stitches along the suture line for one to four courses in the sole adjacent the suture. There is no need to slacken the first few courses

in the sole adjacent the bottom of the heel where there is no suture line.

The increased number of courses in the narrowed segment 110 constituting the heel is produced by manipulation of special narrowing or widening mechanism. As here shown and described, the narrowing is conducted at the regular intervals and widening takes place intermittently. For this purpose the widening picker is shaped and located in a novel manner. By the use of this special picker the number of courses which it takes to narrow the usual or requisite number of needles is increased to any desired extent.

Referring now to the drawings,

Fig. 1 is a diagrammatic view of the outline of a portion of a stocking showing a heel manufactured on a machine in accordance with my invention, the arrowheads on the dot and dash lines indicating the direction in which the knitting is proceeding and the courses being indicated by the dot and dash lines;

Fig. 2 is a diagrammatic showing of the interlooping of the stitches along the suture line of a heel made in accordance with my invention, the particular interlooping shown in this figure being different from Fig. 1;

Fig. 3 is a front elevation of sufficient of the ordinary well-known Scott & Williams type of revolving needle cylinder hosiery machine to show mechanism for intermittently operating the novel widening picker to produce the interlooping of Fig. 2;

Fig. 4 is a plan view from the underside of an improved form of dropper or widening picker used in the mechanism shown in Fig. 3, together with its relation to the needle butts operated thereby;

Fig. 5 is a plan view of a portion of the sinker cam cap with a pivoted cam for pushing sinkers in selectively to cause local slackening of the stitches after the heel is completed;

Fig. 6 is a perspective view of some of the links on the main pattern chain together with the pin for interrupting the operation of the widening picker, the latter being shown in position to interrupt the narrowing in the mechanism shown in Fig. 3; while

Fig. 7 is a plan view similar to Fig. 4 of a modified form of widening picker together with its relation to the needle butts operated thereby.

The manufacture of the stocking will be described as if it were being carried out on the Scott & Williams machine shown and described in the patent to A. E. Page and Frank R. Page No. 1,841,205, dated January 12, 1932, modified as

described below. In that machine the heel and toe pockets are knit on opposite sides of the circle of needles, the heel pocket being knit on the short butt side. The general features of the Scott & 5 Williams type of revolving needle cylinder machine are shown and described in the patent to Robert W. Scott No. 1,152,850, dated September 7, 1915.

In the ordinary manufacture of the narrowed 10 segment of a seamless heel or toe pocket, the active group of needles is shortened one needle at each oscillation of a reciprocation. Thus, as an oscillation starts and before the active group of needles reaches the knitting cams, the leading 15 needle meets a narrowing picker and is raised to idle position. On the oscillation in the opposite direction the other narrowing picker will raise the leading needle at the other end of the active group. By thus narrowing one needle on 20 each course in the segment, the number of courses in the segment is kept equal to the number of needles on which the segment is knit, but this produces a segment which, at the corner 11 of the heel where the point of the segment meets 25 the instep, covers an arc of only about 45°, the lower edge of the segment therefore when completed being at approximately the point 1 of the heel. Such a segment is, of course, of very little use because it does not protect against the wear 30 which occurs on the bottom of the heel at the position where the widened segment of the ordinary present day heel and toe pocket is located. By delaying the narrowing operation so that the heel includes a larger number of courses than 35 there are needles knitting the segment, the segment is made wider and extends underneath the foot a sufficient distance without taking all the additional time necessary to knit a widened segment.

40 In the preferred method of manufacture of my heel as illustrated in Fig. 2 the narrowing operation of the machine is permitted to take place without interruption and the rate of narrowing in the segment is varied by means of intermittent use of the novel widening picker. According to 45 this method, at intervals a needle which has been raised out of action by a narrowing picker is returned into action by the novel widening picker 680. It is found that by varying the active segment of needles in this manner a particularly 50 strong suture is obtained.

Still referring to Fig. 2, the last circular course 55 10 before the heel, indicated by a heavy line at the top of the figure, is knit toward the left hand side of the heel as shown in the drawing, and the first reverse course, i. e., the course marked 12, is knit toward the right, as shown in this figure. The last needle to knit in this course is at the corner 11 of the heel, as defined near the opening 60 of the specification. As soon as the oscillation for the first forward reciprocatory course 23 of the heel starts, the leading needle of the active segment, which is the one knitting the wale at the corner of the heel, is met by the narrowing picker and raised out of action. On the next or 65 second course 24 in the reverse direction, the last needle to knit is the needle in the wale 28 next to the corner 11 of the heel, and on the second forward reciprocatory course 25 that needle is raised out of action before it can knit. On the next course, i. e., the third course 26 in the reverse direction, the dropper or widening picker 680 comes into action. On the oscillation in this 70 direction the needle knitting the wale 28 next to the corner 11 which was raised out of action on

the previous course 25 before it reached the yarn in the knitting cams, is now the leading needle of the inactive segment following the active segment, and therefore meets the dropper or widening picker 680 and is pushed down into position 5 as the last needle of the active group before it reaches the yarn of the cams. Therefore the loop left around the shank of the needle in the wale 28 next to the corner 11 when that needle was raised out of action at the beginning of course 25, is now knit as the stitch in course 26. The cycle just described is repeated throughout the fabric shown in Fig. 2 until the narrowed segment is completed, and the first complete circular course 22 after the knitting of the heel 15 starts on the side of the heel (not shown in the drawings) at the corner 11 of that other side and as a continuation of the partial course 21 near the bottom of the heel. This first complete circular course 22 is indicated in Fig. 2 by a heavy 20 line. In this way it is possible when narrowing at a regular rate and using the widening picker intermittently, to vary the rate of narrowing by varying the intermittency of the use of the dropper or widening picker. 25

As already mentioned, it is desirable to avoid puckering along the suture line R formed by course 21 made at the close of the heel, and this can be accomplished by slackening the stitches along the suture. (The suture line is indicated 30 by a heavy line R in Fig. 1.) Mechanism which can cause this local slackening is well known, and reference is made to the Robert W. Scott Patent No. 1,189,220, dated June 27, 1916, where by using sinkers having different heights of operating butts, certain sinkers can be pushed further in to cause slackening at any desired point in the circle of needles. Such slackening should be caused at the stitches along the suture on each 35 side of the heel. 40

In Fig. 5 is shown means for slackening the stitches locally in the general manner of the Scott Patent 1,189,220 above identified, these means consisting of a cam 38 in the sinker cam cap 398 adapted to press radially inwards sinkers 45 having butts of the proper height, the lever 39 tending to press said pivoted cam 38 radially inward, and any suitable mechanism (not shown) may be provided for operating the lever 39 or acting 50 directly on the cam 38. 55

It is generally not necessary to slacken more than three or four courses.

A mechanism suitable for operating the widening picker or dropper is shown in Figs. 3, 4 and 6, 60 consisting of means actuated from lugs on the left side of the pattern chain to push the widening picker 680 into inoperative position during the making of the heel except when it is desired to slow down the rate of narrowing. The type of lug for causing intermittent operation of the 65 widening picker is indicated in Figs. 3 and 6 by the reference character 80.

It will be noted that it is the absence of the lugs 80 which causes the widening picker to interrupt the narrowing of the segment in Fig. 2. As 70 shown in the drawings, the mechanism for operating the widening picker 680 consists of a bracket 232 on the stud 234 of the machine, identical with the bracket used with the mechanism of Fig. 5, having a pin 236 overlying the left 75 side of the pattern chain, a vertical rod 40 somewhat similar to the rod for interrupting the narrowing pickers but calculated to underlie a bent tail 41 on the widening picker 680, the picker being adapted to be lowered to inoperative 80

position by the raising of the vertical rod 40. The spring-pressed connection between the bracket 232 and the vertical rod 40 consists of a sleeve 36 fixed on the vertical rod 40 and a compression spring 37 between that sleeve 36 and the arm 233 of the bracket, the lower end of the rod passing through the arm 233 of the bracket. The exact amount of movement of the widening picker is determined by a stop rather than by the height of the lugs on the left side of the pattern chain, the stop in this instance being a sleeve 42 fastened on to the vertical rod 40 just below a guide plate 43 on the bedplate B of the machine. The sleeve 42 can be adjusted in proper position by means of a screw 44 therein and the sleeve has a pin 45 projecting upwardly from one side of it through the guide plate 43, this pin 45 being long enough to stay in the hole in the bedplate when the vertical rod 40 is in its lowermost position. The function of this pin in the sleeve is to keep the vertical rod from turning, which would have the effect of bringing its bent upper end out from under the bent tail 41 of the widening pick.

It will be noted that the lugs 80 on the chain (Fig. 6) occupy two-thirds of the length of each chain link, the widening picker 680 being arranged in such a manner that when the rod 40 is raised it is moved to inoperative position and therefore the absence of a lug at this portion of the chain link corresponds to the activity of the widening picker 680 which lengthens the narrowing of the segment of the fabric.

If desired, the rate of narrowing during the making of the segment may be altered from time to time, giving a different shape and causing the suture line to bend in a different manner. Thus, for instance, the rate of narrowing may be changed twice, the first portion A (Fig. 1) being knit with one rate of narrowing and the next portion B being knit with a different rate of narrowing, and the portion C being knit with still a third rate of narrowing. The rate of narrowing may be increased or decreased as the knitting of the segment progresses. An example of the decreased rate of narrowing would be to make the portion A by interrupting the narrowing at every third reciprocation, making the portion B by interrupting the narrowing on every other reciprocation, and then making the portion C by allowing narrowing to proceed in the ordinary manner, narrowing at each end on each reciprocation.

In the fabric shown in Fig. 2 it will be noted that the widening picker returns only one needle to activity at a time. In the modern seamless hosiery machines, however, it is customary to make the widened segment of both the heels or toes by the so-called "two down and one up" method, this requiring that the widening picker lower two needles at a time. It therefore is necessary that the widening picker, when making a stocking according to my invention, be able to lower two needles at a time during the making of the widened segment of the toe, but only one needle at a time during the making of the narrowed segment which constitutes my improved heel.

In the machine shown in the Page Patent 1,841,205 above identified, the heel is manufactured on the short butt side of the circle of needles and the toe is manufactured on the long butt side. I therefore have devised a picker 680 which is shown in Fig. 4, adapted to perform all the operations required to make my heel and

toe in the machine of that Page Patent 1,841,205. This picker 680 has overhangs or lips 681 on each side which are wide enough to take two needles but, as shown in the drawings, the portions of those lips at the end of the picker have notches 682 therein which reduce their width so that at the end of the picker the lips 681 are wide enough to take only one needle each at a time. As shown in Fig. 4, these notches in the ends of the lips 681 are long enough so that the butts of the needles on the short butt side of the needle circle, i. e., on the needles which are active during the making of the heel, will not project far enough from the needle cylinder to reach the wide portion of the lips. It therefore will be obvious that during the making of the heel the picker will take only one needle at a time. On the other hand, during the making of the toe the needles which are to be picked back again into action have butts which are long enough to lie in the path of the wide portions of the lips, and therefore during the making of the toe the dropper will be effective to take two needles at a time. These notched lips can be availed of in making other seamless fabrics to vary any picking in any desired manner by the corresponding arrangement of needle butt lengths. Thus the picker shown in the drawings can pick down one short butt, or one short butt and one long butt. Again, needles can be picked down one and two in alternation or if the wide portion of the lip is wide enough to take three needles (see Fig. 7), then it is possible to pick down a short or long butt needle, skip the next short butt needle and take an adjacent long butt needle. The usual fashion marks can be placed in the foot if desired.

Many modifications of my invention which do not depart from the scope of my invention will occur to those skilled in the art.

I claim:

1. A circular knitting machine having independent needles and operating butts of different lengths on said needles, in combination with a widening picker having a lip for lowering needles to operative position, notched to engage at least one needle and at the same time to engage or miss at least one of the succeeding needles according to whether its butt is long or short.

2. A circular knitting machine having independent needles and operating butts of different lengths on said needles, in combination with a widening picker having a lip for lowering needles to operative position notched to engage the first needle butt and simultaneously to engage at least one adjacent butt if it is a long butt.

3. A circular knitting machine having independent needles and operating butts of different lengths, in combination with a widening picker having a lip for moving needles into operative position, said lip being notched to engage the first needle butt and to engage the second needle butt if long but to miss it if short.

4. A circular knitting machine having independent needles and operating butts of different lengths on said needles, in combination with a widening picker having a lip for moving needles into operative position so shaped as to engage the short butt needles one at a time irrespective of the arrangement of the needles or to engage a plurality of long butt needles at one time.

5. A circular knitting machine having independent needles and operating butts of different lengths on said needles, in combination with a widening picker to pick needles into action, said widening picker having a lip thereon notched to

pick short butt needles into action one at a time or a plurality of longer butt needles into action at the same time.

6. A circular knitting machine having independent needles with short operating butts on one side of the circle and long operating butts on the other side adapted to manufacture stockings having heels and toes, in combination with a widening picker having a lip for moving needles to operative position notched to engage either short butt needles one at a time or a plurality of long butt needles at one time, said widening picker bringing down one short butt needle at a time in the making of the heel and a plurality of long butt needles at a time in the making of the toe.

7. A circular knitting machine having inde-

pendent needles and operating butts of different lengths on said needles, in combination with a widening picker having a lip for lowering needles to operative position, notched to engage the first needle butt and simultaneously to engage whichever of the next two needles have long butts.

8. A circular knitting machine having independent needles and operating butts of different lengths on said needles, in combination with a widening picker having a lip for lowering into operative position a plurality of needles at a time so shaped as to limit the operation of the shorter butt needles to one at a time irrespective of the arrangement of the needles.
